[57] **ABSTRACT**

This invention relates to a wall flow correction of an engine having a fuel injector that injects fuel towards a fuel adhesion part such as an air intake valve. An equilibrium adhesion mount of fuel adhering to a fuel adhering part and a quantity proportion are computed based on a cooling water temperature in a temperature equilibrium state. The adhesion amount of fuel adhering to the fuel adhering part is also predicted at the present time, and the temperature of the fuel adhering part is estimated. A temperature difference between a detected cooling water temperature and estimated fuel adhering part temperature is computed, and an adhesion rate is calculated based on this equilibrium adhesion amount, quantity proportion, predicted adhesion amount and temperature difference. A basic injection amount is corrected using this adhesion rate, and the precision of air-fuel ratio control immediately after start-up when the temperature of the fuel adhering part is in a non-equilibrium state, is improved.

ENGINE AIR-FUEL RATIO CONTROLLER

FIELD OF THE INVENTION

This invention relates to an engine air-fuel ratio controller, and more specifically, to a transient correction of a fuel injection amount during engine start-up.

BACKGROUND OF THE INVENTION

In air-fuel ratio control of a fuel mixture supplied to an engine, deviation of an air-fuel ratio during engine acceleration/deceleration from a target value is often related to so-called wall flow of fuel. Wall flow refers to a phenomenon wherein, for example, fuel injected from a fuel injection nozzle adheres to an engine intake valve or intake port, and flows down walls into a cylinder as a liquid. Due to the fact that the flowrate of this wall flow varies depending on the acceleration/deceleration of the engine, the air-fuel ratio of the fuel mixture also varies.

In air-fuel ratio control, the fuel supply amount is usually corrected by considering oversupply or undersupply of fuel due to wall flow as a transient correction amount.

For example, an equilibrium adhesion mount M_{fh} and quantity proportion K_{mf} are first determined according to an engine load, engine speed N_e and cooling water temperature T_w , and an adhesion rate V_{mf} is found from a mathematical expression using these values.

The equilibrium adhesion amount M_{fh} is a fuel adhesion amount in a steady state determined by the engine speed and temperature of a fuel adhering part. The quantity proportion K_{mf} is a factor indicating the extent to which a difference ($M_{fh}-M_f$) between the equilibrium adhesion amount M_{fh} and an adhesion amount M_f at present can be reflected in a correction of fuel injection amount. The adhesion rate V_{mf} is an adhesion amount per unit fuel injection period (per unit injection), and a basic fuel injection amount T_p is corrected by this adhesion rate V_{mf} .

However, in the case of an engine where the fuel injection nozzle injects fuel towards the intake valve, a large error appears in the air-fuel ratio when the equilibria adhesion amount M_{fh} and quantity proportion K_{mf} are computed from the cooling water temperature T_w , and this is especially true immediately after a cold start. In this case, the wall flow fuel amount is affected by the temperature of the intake valve on the surface of which the wall flow is flowing, and the temperature difference between the valve temperature and cooling water temperature T_w leads to an error in the estimate of wall flow.

In this context, Tokkai Hei 1-305142 published by the Japanese Patent Office in 1989 discloses a method wherein the valve temperature is first estimated, and the valve temperature is used instead of the cooling water temperature T_w for computing M_{fh} and K_{mf} . Immediately after start-up, the valve temperature is effectively the same as the cooling water temperature T_w , and it levels off to a temperature that is higher than T_w by a constant value (e.g. approx. 80°C.). Also, the variation of the valve temperature is a first order delay depending on a time constant determined by the engine air intake volume. A predicted valve temperature T_f can therefore be found from the following equation:

$$T_f = T_h \cdot SPTF + T_{f-1} \cdot (1 - SPTF) \quad (1)$$

wherein, T_{f-1} is the value of T_f on the immediately preceding occasion.

An equilibrium intake valve temperature T_h and delay time constant $SPTF$ are first determined using the engine load and speed as parameters.

In Tokkai Hei 3-134237 published by the Japanese Patent Office in 1991, a wall flow correction temperature T_{wf} which converges toward the cooling water temperature T_w with a first order delay, is used instead of the cooling water temperature T_w .

According to the aforesaid embodiment, the data used for calculating M_{fh} and K_{mf} correspond to the case where the valve temperature has levelled off to the temperature which is higher by a predetermined amount, i.e. to an equilibrium temperature state, when the cooling water temperature T_w is constant. Consequently, in a non-equilibrium temperature state, M_{fh} and K_{mf} found using this data contain an appreciable error. As a result, a transient correction amount of a non-equilibrium temperature state may still contain an appreciable error, since calculations are performed based on M_{fh} , K_{mf} which have large errors even when a non-equilibrium temperature state is simulated using the wall flow correction temperature T_{wf} instead of the cooling water temperature T_w .

More specifically, in the aforesaid methods, the equilibrium temperature state wherein $T_{wf}=40^\circ C.$ (cooling water temperature $T_w=40^\circ C.$) and the non-equilibrium temperature state wherein $T_{wf}=40^\circ C.$ (cooling water temperature T_w is not $40^\circ C.$) are considered as being the same. This tends to cause errors in the a-fuel ratio immediately after start-up when non-equilibrium temperature conditions prevail continuously.

SUMMARY OF THE INVENTION

It is therefore an object of this invention to improve the precision of air-fuel ratio control immediately after the engine start-up when the intake valve temperature or wall flow correction temperature is in a non-equilibrium state.

In order to achieve the above object, this invention provides a fuel injection controller for an engine in which fuel is injected towards a fuel adhering part from a fuel injector. The controller comprises a mechanism for computing a basic fuel injection amount, a mechanism for detecting an engine cooling water temperature, a mechanism for computing an equilibrium amount of the injected fuel adhering to the fuel adhering part based on a cooling water temperature in an equilibrium state, a mechanism for computing a quantity proportion based on the cooling water temperature in the equilibrium state, a mechanism for predicting an amount of injected fuel that will adhere to the fuel adhering part at a present time, a mechanism for estimating a temperature of the fuel adhering part, a mechanism for computing a temperature difference between the cooling water temperature and the temperature of the fuel adhering part, a mechanism for computing an adhesion rate based on the equilibrium adhesion amount, the predicted adhesion amount, the quantity proportion and the temperature difference, a mechanism for correcting the basic injection amount and computing a fuel injection amount based on the adhesion rate, and a mechanism for supplying the fuel injection amount to the fuel injector.

According to an aspect of this invention, the adhesion rate computing mechanism comprises a mechanism for correcting the equilibrium adhesion amount according to the temperature difference, and a mechanism for computing an adhesion rate by multiplying a difference between a corrected equilibrium adhesion amount and the predicted adhesion amount, by the quantity proportion.

In this case, it is preferable that the equilibrium adhesion amount correcting mechanism further corrects the equilibrium adhesion amount according to any one of the cooling

water temperature, the fuel adhering part estimated temperature and the cooling water temperature during engine start-up.

It is also preferable that the equilibrium adhesion amount correcting mechanism further corrects the equilibrium adhesion amount according to an engine load.

According to another aspect of this invention, the adhesion rate computing mechanism comprises a mechanism for correcting the quantity proportion according to the temperature difference, and a mechanism for calculating an adhesion rate by multiplying a difference between the equilibrium adhesion amount and the predicted adhesion amount, by a corrected quantity proportion.

In this case, it is preferable that the quantity proportion correcting mechanism further corrects the quantity proportion according to any one of the cooling water temperature, the fuel adhering part estimated temperature and the cooling water temperature during engine start-up.

It is also preferable that the quantity proportion correcting mechanism further corrects the quantity proportion according to an engine load.

According to yet another aspect of this invention, the adhesion rate computing mechanism comprises a mechanism for calculating an adhesion rate by multiplying a difference between the equilibrium adhesion amount and the predicted adhesion amount by the quantity proportion, and a mechanism for correcting the adhesion rate according to the temperature difference.

In this case, it is preferable that the adhesion rate correcting mechanism further corrects the quantity proportion according to any one of the cooling water temperature, the fuel adhering part estimated temperature and the cooling water temperature during engine start-up.

It is also preferable that the adhesion rate correction mechanism further corrects the adhesion rate according to an engine load.

According to yet another aspect of this invention, the adhesion amount prediction mechanism updates the predicted adhesion amount on every fuel injection by adding the adhesion rate to the predicted adhesion amount.

The details as well as other features and advantages of this invention are set forth in the remainder of the specification and are shown in the accompanying drawings.

BRIEF DESCRIPTION OF THE DRAWINGS

FIG. 1 is a schematic diagram of an air-fuel ratio controller according to this invention.

FIG. 2 is a flowchart showing a process of computing a wall flow correction temperature Twf according to this invention.

FIG. 3 is a diagram showing a characteristic of an initial value In wft of the wall flow correction temperature according to this invention.

FIG. 4 is a diagram showing a characteristic of a temperature change proportion Fltsp during combustion according to this invention.

FIG. 5 is a flowchart showing an initialization process of the wall flow correction temperature according to this invention.

FIGS. 6A-6E are diagrams showing variations of a throttle opening TVO, cooling water temperature Tw, wall flow correction temperature Twf and fuel injection pulse width Ti immediately after an engine start-up according to this invention.

FIGS. 7A-7D are diagrams showing variations of a throttle opening TVO, cooling water temperature Tw, wall flow correction temperature Twf and fuel injection pulse width Ti during an engine warm-up according to this invention.

FIG. 8 is a flowchart showing a process of computing a transient correction amount Kathos according to this invention.

FIG. 9 is a flowchart showing a process of computing a fuel injection pulse width Ti according to this invention.

FIG. 10 is a flowchart showing a process of outputting the fuel injection pulse width Ti and computing an equilibrium adhesion amount Mfh for the next injection according to this invention.

FIG. 11 is a diagram showing a characteristic of a correction factor Mfhas related to an equilibrium adhesion amount Mfh during temperature non-equilibrium according to this invention.

FIG. 12 is a diagram showing a characteristic of a correction factor Kmfas related to a quantity proportion Kmf during temperature non-equilibrium according to this invention.

FIGS. 13A and 13B are diagrams showing variations of an adhesion amount Mf, the adhesion amount Mfh and the temperature Twf immediately after the engine start-up according to this invention.

FIGS. 14A-14D are diagrams showing variations of a fuel adhering part temperature, the adhesion amount, the air-fuel ratio and an adhesion rate immediately after the engine start-up according to this invention.

FIG. 15 is a flowchart showing a process of computing the transient correction amount Kathos according to a fourth embodiment of this invention.

FIGS. 16A-16C are diagrams describing an effect of differences of the cooling water temperature Tw on wall flow correction temperature Twf.

DESCRIPTION OF THE PREFERRED EMBODIMENTS

Referring to FIG. 1 of the drawings, intake air of an engine 1 is supplied from an air cleaner 13 via an air intake pipe 8. Fuel is injected from a fuel injection valve 7 towards an air intake valve 14 of the engine 1 based on a fuel injection signal output by a control unit 2 (abbreviated as C/U in the figure). Gas burnt in cylinders of the engine is led into a catalytic converter 10 via an exhaust pipe 9, and after noxious components (CO, HC, NOx) of the burnt gas are removed by a three-way catalyst in the catalytic converter 10, the gas is expelled to the atmosphere.

An intake air volume Qa is detected by a hot wire air flow meter 6. The air volume Qa is controlled by an intake air throttle valve 5 operating concurrently with an accelerator pedal.

An air volume signal from an air flow meter 6 is input to the control unit 2 together with signals from an air-fuel ratio sensor 3 which detects an oxygen concentration of the exhaust gas, a crank angle sensor 4 which outputs a crank-shaft reference position signal (Ref signal) and a crankshaft rotation angle signal, a water temperature sensor 11 which detects a cooling water temperature Tw of a water jacket, and a starter switch 12 which detects an operation of a starter motor that cranks up the engine 1.

The control unit 2 computes a basic injection pulse width Tp from the intake air volume Qa and engine rotation speed No. During acceleration and deceleration, fuel correction is

performed by adding a transient correction mount Kathos to T_p . Specifically, the transient correction mount Kathos is a correction which is applied to fuel wall flow, and it is applied not only when the vehicle is accelerating or decelerating, but also during the engine start-up when the fuel wall flow is largely varying.

The wall flow flowrate largely depends on the temperature of the part where wall flow is set up. Consequently, when all or some of the fuel is injected by the fuel injection valve 7 towards the valve 14, the temperature of the valve 14 is estimated, and the transient correction amount Kathos is computed using a predicted valve temperature T_f .

The valve temperature is effectively equal to the cooling water temperature T_w immediately after the engine start-up, and after the engine is warmed up, it levels off to a temperature higher than T_w by a constant value (e.g. approx. 80°C.). The variation during this time is a first order delay depending on a time constant determined by the intake air volume.

The control unit 2 computes a wall flow correction temperature according to a flowchart shown in FIG. 2. This computation process is known in the art from the aforesaid prior art Tokkai Hei 3-134237.

This computation process is executed at a fixed interval, e.g. once every 1 sec.

In a step S1, it is determined whether or not combustion is taking place in the engine 1, i.e. whether or not fuel supply has been cut, and if combustion is not taking place, the routine proceeds to a step S2.

In the step S2, an initial value In_wft of the wall flow correction coefficient is found from the present cooling water temperature by referring to a map shown in FIG. 3. In this figure, the dot-and-dash line corresponds to $In_wft = T_w$. Herein, as fuel is injected towards the valve 14, the initial value In_wft is set to a value less than T_w as shown by the solid line according to the proportion of fuel injected towards the valve 14 shown on the map.

In a step S3, it is determined whether or not the engine is rotating, and in a step S4, it is determined whether or not the starter switch is ON.

When the engine is rotating and the starter switch is ON, it is determined that the vehicle is in a state immediately prior to starting. In this case and in the case that the engine is not rotating in the step S3, the routine proceeds to a step S5, and the wall flow correction temperature Twf is calculated using the wall flow correction temperature initial value In_wft .

$$Twf = In_wft \cdot ENSTSP\# + Twf_{-1sec} \cdot (1 - ENSTSP\#) \quad (2)$$

where,

Twf_{-1sec} =value of Twf one second previously and

$ENSTSP\#$ =temperature change proportion prior to the engine start-up or while the engine is not operating (constant)

After calculating the wall flow correction temperature Twf by the aforesaid first order delay, the routine of FIG. 2 is terminated.

On the other hand, when fuel is being burnt in the step S1, a temperature change proportion $Flstp$ during combustion is calculated in a step S6 from the intake air volume Q_a by referring to a map shown in FIG. 4. In a step S7, the wall flow correction temperature Twf during combustion is calculated using the present cooling water temperature T_w , and the routine of FIG. 2 is terminated.

$$Twf = T_w \cdot Flstp + Twf_{-1sec} \cdot (1 - Flstp) \quad (3)$$

In the map shown in FIG. 4, the reason why the value of $Flstp$ is increased the higher the value of Q_a , is that the heat of combustion per unit time increases for higher Q_a , and heat is transmitted earlier to the fuel adhering part.

The routine of FIG. 5 shows a process for initializing the wall flow correction temperature performed by the control unit 2. In a step S11, the initial value $Inwft$ of the wall flow correction temperature is calculated from the present cooling water temperature T_w , and $Twf = Inwft$ is set in the step S12.

During warm-up, the wall flow correction temperature Twf is almost identical to the cooling water temperature T_w as shown in FIG. 7C, but after start-up, it converges from the initial value $Inwft$ of the wall flow correction temperature to the cooling water temperature T_w as shown in FIG. 6D.

Ig/SW in FIGS. 6A and 7A denotes ignition switch, and Starter/SW in FIG. 6B denotes starter switch.

The flowchart of FIG. 8 shows a process whereby the transient correction Kathos is computed by the control unit 2.

This routine is executed at intervals of 10 ms. Steps S22, S23, S24, S26 and S27 will be described later.

First, in a step S21, the equilibrium adhesion amount Mfh is computed using the three parameters Ne , T_p , Twf . It is for example determined where the actual cooling water temperature T_w is situated within the temperature ranges divided by the reference temperatures T_{w0} , T_{w1} , T_{w2} , T_{w3} , T_{w4} ($T_{w0} > T_{w1} > T_{w2} > T_{w3} > T_{w4}$). When $T_{w1} > T_w$, map values Mfh_0 and Mfh_1 corresponding to Ne and T_p are calculated from a map corresponding to the reference temperature T_{w0}

which is the nearest temperature higher than T_w , and a map corresponding to the reference temperature T_{w1} which is the nearest temperature lower than T_{w1} . Mfh is then calculated by the following linear interpolation equation using these values Mfh_0 , Mfh_1 , the reference temperatures T_{w0} , T_{w1} , and the present cooling water temperature T_w .

$$Mfh = Mfh_0 + (Mfh_1 - Mfh_0) \cdot \frac{T_w - T_{w0}}{T_{w1} - T_{w0}} \quad (4)$$

The equilibrium adhesion amounts Mfh_0 – Mfh_4 corresponding to the reference temperatures T_{w0} – T_{w4} are first found by observation using the Ne and T_p as parameters.

The calculation of Mfh is however not limited to the above method, and it may be found also from the following relation as disclosed in the aforesaid Tokkai Hei 3-134237.

$$Vfh = T_p \cdot Mfh_{tvo} \quad (5)$$

where, Mfh_{tvo} =adhesion magnification

In a step S25, the extent to which the adhesion mount (estimated parameter Mf) approaches the calculated value of Mfh in unit time (e.g. for one rotation of the crankshaft), is computed as a coefficient Kmf (referred to as a quantity proportion) from the product of a basic quantity proportion $Kmfat$ and a quantity proportion rotation correction factor $Kmfn$. The adhesion mount Mf will be described later.

The basic quantity proportion $Kmfat$ is found from T_p and T_w by referring to a map. $Kmfat$ is set to increase the higher the value of T_p . The quantity proportion rotation correction factor $Kmfn$ is found from Ne by referring to a map. $Kmfn$ is set to become larger the smaller the value of Ne .

In a step S28, the value of Kmf thus found is multiplied by the difference between Mfh and the adhesion mount Mf at the present time.

$$Vmf = (Mfh - Mf) \cdot Kmfn \quad (6)$$

Mf is an estimated parameter of the adhesion mount at that time, and $(Mfh - Mf)$ indicates the excess or insuffi-

ciency compared to the equilibrium adhesion mount. This value (M_{fh} – M_f) is further corrected by the quantity proportion K_{mf} .

After the adhesion rate V_{mf} is calculated, in steps S29 and S30, V_{mf} is further corrected by a correction factor G_{fh} for preventing over-lean during deceleration when light fuel is used, the transient correction mount K_{mf} for the basic injection pulse width T_p is found, and the routine is terminated.

The flowchart of FIG. 9 shows a process for adding the transient correction amount K_{mf} in order to compute a final fuel injection pulse width T_i . This process is also executed at intervals of 10 ms by the control unit 2.

In a step S31, a basic injection pulse width

$$T_p = \frac{Q_a}{N_e} \cdot K, \text{ where } K \text{ is a constant} \quad (7)$$

which for example gives the stoichiometric air-fuel ratio is calculated from the intake air volume Q_a and engine speed N_e . In the step S2, a value obtained by adding the transient correction K_{mf} to this value, is multiplied by a feedback correction coefficient a and another correction coefficient COEF based on the output of the air-fuel ratio sensor 3, and an ineffectual pulse width T_s is added to give the final fuel injection pulse width T_i .

The flowchart of FIG. 10 shows a process executed by the control unit 2 in synchronism with the injection timing (more specifically, the Ref signal). When a predetermined injection timing is reached, the fuel injection pulse width computed in FIG. 9 is transferred to an output register in a step S41, and fuel injection is then performed.

In a step S42, an adhesion amount M_f used in the next routine is determined using the adhesion rate V_{mf} obtained by the aforesaid equation (6).

$$M_f = M_{f-1,Ref} + V_{mf} \quad (7)$$

$M_{f-1,Ref}$ in Equation (7) signifies an adhesion amount when the immediately preceding injection is completed, i.e. before unit rotation. The value obtained by adding V_{mf} during the present injection to this value, is the adhesion mount M_f when the present injection is complete, and this adhesion amount M_f is used for calculating the V_{mf} on the next occasion. Whereas M_f in Equation (6) is the value immediately prior to computation of V_{mf} , M_f on the left-hand side of Equation (7) is the value immediately after computation of V_{mf} . The value of M_f in Equation (6) is therefore substituted in $M_{f-1,Ref}$ on the right-hand side of Equation (7) so as to calculate M_f on the left-hand side of Equation (7). The reason why M_f and $M_{f-1,Ref}$ both appear in Equation (7) is because it is necessary to update the immediately preceding value and the present value so as to update the adhesion mount cyclically per unit rotation. M_f is updated by the above equation when fuel is injected and the initial value of M_f is predetermined according to the cooling water temperature T_w at the engine start-up.

The data required to calculate M_{fh} and K_{mf} , i.e. the map values M_{fh_0} – M_{fh_4} and the basic quantity proportion K_{mf} , are based on the cooling water temperature in the equilibrium temperature state, hence M_{fh_0} – M_{fh_4} and K_{mf} in the equilibrium state do not necessarily correspond to actual values. This means that the desired accuracy is not obtained merely by using the wall flow correction temperature T_{wf} instead of the cooling water temperature. In other words, M_{fh} is less than the desired value when it is calculated from T_{wf} in FIG. 13B, and the variation of M_f with K_{mf} found from T_{wf} is more rapid than the desired variation, as shown in FIG. 13A.

Further, consider the cases for a 20° C. equilibrium temperature state, start-up from a cooling water temperature $T_w=40$ ° C., and start-up from a cooling water temperature $T_w=80$ ° C., as shown in FIGS. 16A–16C. It will be assumed for the sake of convenience that the cooling water temperature T_w is invariant. In the case of FIG. 16A, T_{wf} is constant at 20° C., so the data for M_{fh} , K_{mf} in the temperature equilibrium state may be used without modification. In the cases of FIGS. 16B and 16C, however, a temperature non-equilibrium correction must be applied to the data for temperature equilibrium. Also, a larger correction is required for the case of FIG. 16C, when a difference ΔT_{wf} between T_w and T_{wf} is larger.

According to this invention, suitable data for cooling water temperature in the temperature equilibrium state is searched based on the detected value T_w of cooling water temperature, M_{fh} and K_{mf} are computed, and a correction factor for temperature non-equilibrium is computed according to the temperature difference ΔT_{wf} between T_w and T_{wf} .

M_{fh} and K_{mf} are then corrected by this correction factor for temperature non-equilibrium. More specifically, the steps S22, S23, S24, S26 and S27 in the routine of FIG. 8 correspond to this process.

First, in the step S22 of FIG. 8, the temperature difference ΔT_{wf} between T_w and T_{wf} is computed. In the step S23, a map in FIG. 11 is searched from this temperature difference ΔT_{wf} , and a correction factor $M_{fh,as}$ for temperature non-equilibrium corresponding to M_{fh} , is found. In a step S24, M_{fh} is corrected by multiplying M_{fh} calculated in the step S1 by this correction factor $M_{fh,as}$.

Likewise, a map shown in FIG. 12 is searched from the temperature difference ΔT_{wf} , and a correction factor $K_{mf,as}$ for temperature non-equilibrium corresponding to K_{mf} is found. In the step S27, K_{mf} is corrected by multiplying K_{mf} found in the step S25, by the correction factor $K_{mf,as}$.

Herein, $M_{fh,as}$ is a value which increases the larger the temperature difference ΔT_{wf} , as shown in FIG. 11. $K_{mf,as}$ is a value which decreases the larger the temperature difference ΔT_{wf} , as shown in FIG. 12. The characteristics of these correction factors $M_{fh,as}$, $K_{mf,as}$, may be deduced from FIGS. 13A and 13B. The difference between M_{fh} calculated from T_{wf} and the desired value M_{fh} , and the difference between K_{mf} calculated from T_{wf} and the desired value K_{mf} , are both largest immediately after start-up, and they decrease the smaller the temperature difference ΔT_{wf} between T_w and T_{wf} . The desired values are values required by actual transient conditions, and may be found from experiment or analysis.

The aforesaid characteristics correspond to the fact the temperature difference ΔT_{wf} is largest immediately after start-up, and that it gradually decreases with elapsed time after start-up. It may be conjectured that the non-equilibrium state of the retake air valve temperature is more significant for a larger temperature difference ΔT_{wf} .

Now, referring to FIGS. 14A–14D, consider the case where M_{fh} required for the non-equilibrium state is larger than M_{fh} required for the equilibrium state. In FIGS. 14C and 14D the dotted lines correspond to the aforesaid prior art, and the thick lines correspond to this invention.

According to this invention, M_{fh} and K_{mf} obtained using T_w are corrected by the correction factors $M_{fh,as}$ and $K_{mf,as}$ for temperature non-equilibrium. In other words, M_{fh} is corrected by $M_{fh,as}$ to a larger value than for temperature equilibrium, and K_{mf} is corrected by $K_{mf,as}$ so that the response of M_f is smaller than the response required for temperature equilibrium. As a result, M_{fh} and M_f coincide with the values required for temperature non-equilibrium, V_{mf} approaches the value required for temperature non-

equilibrium, and any tendency of the air-fuel ratio toward lean immediately after start-up is prevented.

Next, a second embodiment of this invention will be described.

In the aforesaid controller, the correction factors Mfhas and Kmfas for temperature non-equilibrium are found based on $\Delta T_{wf} = T_w - T_{wf}$. According to the second embodiment, T_w , T_{wf} or the water temperature at the engine start-up are further used along with ΔT_{wf} as parameters to specify Mfhas and Kmfas. By setting the correction factors even more finely in this way, the correction of temperature non-equilibrium is made more reliable.

According to a third embodiment of this invention, in addition to $\Delta T_{wf} = T_w - T_{wf}$, engine load is assigned as a parameter of Mfhas and Kmfas.

In general, the correction factor Mfh increases the higher the engine load. This is because the wall flow tends to vaporize more easily as the intake pipe pressure approaches atmospheric pressure from a higher pressure. It is therefore desirable that the correction factors Mfhas and Kmfas for temperature non-equilibrium vary according to the engine load. The temperature non-equilibrium correction factors Mfhas and Kmfas are then obtained with good precision even when the engine load is different in the temperature non-equilibrium state.

Three parameters may also be used to find Mfhas and Kmfas, i.e. the temperature difference between T_w and T_{wf} , any one of T_w , T_{wf} or the cooling water temperature, and the engine load.

The flowchart of FIG. 15 shows a fourth embodiment of this invention. This chart corresponds to the chart of the first embodiment of FIG. 8.

According to the preceding three embodiments, both Mfh and Kmf were corrected for the temperature non-equilibrium state. Although this would provide a reliable correction, however, it is not easy to obtain precise values for the two correction factors Mfhas and Kmfas immediately after engine start-up.

According to the fourth embodiment, Vmf (or Kathos) during temperature equilibrium are corrected for temperature non-equilibrium. More specifically, in steps S51 and S52 of FIG. 15, a correction factor Vmf as for temperature non-equilibrium corresponding to Vmf is found from the temperature difference ΔT_{wf} between T_w and T_{wf} by referring to a predetermined map. Vmf in the step S8 is multiplied by this correction factor Vmfas, and a new value of after correction is found.

According to the fourth embodiment, the correcting elements comprise only one constant, so the number of correcting steps is less than in the case of the preceding three embodiments. The inventors found experimentally that this did not lead to any loss of precision in the air-fuel ratio immediately after start-up.

As in the case of the aforesaid first to third embodiments, the parameters used to find Vmfas may be the temperature difference ΔT_{wf} between T_w and T_{wf} (corresponding to the first embodiment), the temperature difference ΔT_{wf} together with T_w , T_{wf} or water temperature at the engine start-up (corresponding to the second embodiment), or the temperature difference ΔT_{wf} together with the engine load (corresponding to the third embodiment).

In an "L-jetronic type multi-point injection system", the engine load which serves as a parameter to find Mfhas, Kmfas and Vmfas may be expressed by the basic injection pulse width T_p and intake air volume Q_a , but in a "D-jetronic type multi-point injection system", the intake pipe negative pressure may be used. In an " α -N type

multi-point injection system", an α -N flowrate QH_o may be used as the engine load.

According to the aforesaid embodiments, the wall flow correction temperature T_{wf} was used as the air Intake valve estimated temperature T_f , however it will be understood that the intake valve estimated temperature T_f of Equation (1) may itself be used instead.

The embodiments of this invention in which an exclusive property or privilege is claimed are defined as follows:

1. A fuel injection controller for an engine in which fuel is injected towards a fuel adhering part from a fuel injector, comprising:

means for computing a basic fuel injection amount,
means for detecting an engine cooling water temperature,
means for computing an equilibrium amount of said injected fuel adhering to said fuel adhering part based on a cooling water temperature in an equilibrium state,
means for computing a quantity proportion based on said cooling water temperature in said equilibrium state,
means for predicting an amount of injected fuel that will adhere to said fuel adhering part at a present time,
means for estimating a temperature of said fuel adhering part,
means for computing a temperature difference between said cooling water temperature and the temperature of said fuel adhering part,
means for computing an adhesion rate based on said equilibrium adhesion amount, said predicted adhesion amount, said quantity proportion and said temperature difference,
means for correcting said basic injection amount and computing a fuel injection amount based on said adhesion rate, and
means for supplying said fuel injection amount to said fuel injector.

2. A fuel injection controller as defined in claim 1, wherein said adhesion rate computing means comprises means for correcting said equilibrium adhesion amount according to said temperature difference, and means for computing an adhesion rate by multiplying a difference between a corrected equilibrium adhesion amount and said predicted adhesion amount, by said quantity proportion.

3. A fuel injection controller as defined in claim 2, wherein said equilibrium adhesion amount correcting means further corrects said equilibrium adhesion amount according to any one of said cooling water temperature, said fuel adhering part estimated temperature and said cooling water temperature during engine start-up.

4. A fuel injection controller as defined in claim 2, wherein said equilibrium adhesion amount correcting means further corrects said equilibrium adhesion amount according to an engine load.

5. A fuel injection controller as defined in claim 1, wherein said adhesion rate computing means comprises means for correcting said quantity proportion according to said temperature difference, and means for calculating an adhesion rate by multiplying a difference between said equilibrium adhesion amount and said predicted adhesion amount, by a corrected quantity proportion.

6. A fuel injection controller as defined in claim 5, wherein said quantity proportion correcting means further corrects said quantity proportion according to any one of said cooling water temperature, said fuel adhering part estimated temperature and said cooling water temperature during engine start-up.

7. A fuel injection controller as defined in claim 5, wherein said quantity proportion correcting means further corrects said quantity proportion according to an engine load.

8. A fuel injection controller as defined in claim 1, wherein said adhesion rate computing means comprises means for calculating an adhesion rate by multiplying a difference between said equilibrium adhesion amount and said predicted adhesion amount by said quantity proportion, and means for correcting said adhesion rate according to said temperature difference.

9. A fuel injection controller as defined in claim 8, wherein said adhesion rate correcting means further corrects

said quantity proportion according to any one of said cooling water temperature, said fuel adhering part estimated temperature and said cooling water temperature during engine start-up.

10. A fuel injection controller as defined in claim 8, wherein said adhesion rate correcting means further corrects said adhesion rate according to an engine load.

11. A fuel injection controller as defined in claim 1, wherein said adhesion amount predicting means updates said predicted adhesion amount on every fuel injection by adding said adhesion rate to said predicted adhesion amount.
